UNITED STATES PATENT OFFICE.

WALTER RENDTORFF, OF MAYWOOD, ILLINOIS.

LAND AND WATER TOY.

1,386,425.

Specification of Letters Patent.

Patented Aug. 2, 1921.

Application filed October 11, 1920. Serial No. 415,989.

To all whom it may concern:

Be it known that I, WALTER RENDTORFF, a citizen of the United States, residing at Maywood, county of Cook, and State of Illinois, have invented certain new and useful Improvements in Land and Water Toys, of which the following is a specification.

This invention relates to a toy which can be used either on land or in the water, and 10 the principal object of the invention is to provide a toy of this kind in which land and water wheels are provided for operating movable parts upon the toy. The invention consists in the novel construction, combination 15 and arrangement of the several parts.

In the accompanying drawings, Figure 1 is a side elevation of a toy constructed in accordance with the principles of this invention; Fig. 2 is a plan view looking at 20 the bottom of the toy showing the construction and operating parts; and Fig. 3 illustrates another form of the toy.

Referring more particularly to the drawings, the body 1 of the toy is preferably in 25 the form of an animal which is able to move both upon the land and in the water, such for example, as a crab, an alligator or a turtle, as shown, but of course the body may be of some fanciful design or it may be 30 a boat with wheels, or the like. This body is preferably made of wood or may be of any buoyant material or construction, so that it will float in the water. The underside of the body is preferably hollowed out 35 or formed with a recess 2 on the bottom side thereof, leaving supporting rims or edges 3 at the sides.

A head 4 and a tail 5, or any other suitable 40 projections may be pivoted within the recess 2 at the underside of the body extending therefrom through appropriate spaces between the rims 3 to permit a limited swinging movement.

Mounted on projections 6 at the sides 45 of the body are paddle wheels 7, secured thereto in any ordinary way by means of an axle 8, with a washer 9 interposed between the wheel and its supporting section 6.

Each wheel is formed with a circular disk 50 or rim 10 and with projecting vanes 11 at right angles to the rim. It is obvious that these wheels will support the body for free rolling movement on the land, and that if the body is drawn through the water, the 55 paddle wheels will be rotated by such movement. For this purpose a hook 12 may be

attached to the head or body for fastening a drawing string thereto.

In order to positively oscillate or move the head and tail as the toy is moved in land or water, these parts may be provided with extensions 14 and 15 which may be connected by means of a bar 16. An additional paddle wheel 17 is mounted in the underside of the body in brackets 18 upon a shaft 19 which has a crank 20 at one end connected by means of a link 21 with one or both of the extensions 14 or 15. It is obvious that the rotation of this paddle wheel 17 will produce a corresponding movement of the head and tail 4 and 5 through the links 16 and 21.

Instead of the construction shown in Fig. 2, one or both of the opposite paddle wheels 7 at the sides of the toy may be mounted upon a shaft 22 which extends within the recess 2 of the body and this shaft may be provided with a crank portion 23 connected by means of a link 24, with an extension 25 from the head or tail. It is obvious that this construction will also cause the oscillation of the head or tail, or any other parts, by the movement of the paddle wheels on land or in the water.

Although this construction is very simple, it is satisfactory to operate, because the toy can be drawn directly from the water on to the land or vice versa, and the head and tail continue to move in either element because of the rotation of the combined land and water wheels. It is obvious that other body forms and other operating constructions may be adopted without departing from the spirit and scope of my invention.

I claim:

1. A land and water toy having a buoyant body, and a supporting wheel for the body upon which the toy may be moved on the land, the wheel being provided with projecting vanes which rotate the wheel as the toy is drawn through the water.

2. A wheeled toy having a buoyant body, a movable member pivoted upon the body, and a paddle wheel which is rotated by the movement of the toy on land or in water having a crank connection with said member for positively moving it in accordance with the movement of the wheel.

3. In a wheeled toy of the class described, a body, a paddle wheel rotatable as the toy is moved on the land or in the water, a member pivoted to the body and projecting

therefrom, and means connecting the member with the paddle wheel for positive oscillating movement in accordance with the rotation thereof.

5. 4. In a wheeled toy, a body, a projecting member pivoted on the body for limited oscillation, a paddle wheel rotatable on the land or in the water, and means including a crank connecting the paddle wheel and the member for oscillating the projecting member in accordance with the rotation of the paddle wheel.
- 10 5. In a toy, a body, a head and tail piv-

oted thereto and projecting from the body, a plurality of wheels upon which the body 15 is mounted, one or more of the wheels being formed with projecting vanes which adapt them to be rotated when the toy is drawn along on land or in the water, and means including a shaft with a crank portion attached to the vaned wheel, and a linkage connecting the crank with the head and tail to oscillate them in accordance with the movement of the wheel.

WALTER RENDTORFF.
